ELECTRICALLY DRIVEN HAIR CLIPPER
AND THE LIKE

Sidney Adolph Horstmann, Bath, England

Application July 9, 1946, Serial No. 682,194
In Great Britain August 2, 1945

3 Claims. (Cl. 30—221)

1

This invention relates to improvements in electrically driven hair clippers and the like of the kind provided with means whereby they may be adapted to cut the hair to different lengths, and has for its chief object to provide a novel, simple and efficient method of effecting the desired adjustment.

In an electrically driven hair clipper or the like according to the present invention, the thickness of the lower, fixed, comb or cutter increases from the front rearwardly and means are provided for adjusting the longitudinal position of the upper, oscillating, comb or cutter relative to the lower cutter so that it may be effective to cut the hair to different lengths.

Preferably the upper cutter is carried by the forward ends of a bridle piece which extends rearwardly within the casing and at its rear end is pivoted on a pin, the position of which is adjustable to produce the desired backward and forward movement of the upper cutter.

Several additional novel and advantageous features of construction and arrangement are provided by the present invention and are fully described hereinafter and claimed in the appended claims.

In order that this invention may be the more clearly understood and readily carried into effect, I will proceed to describe the same with reference to the accompanying drawings, which illustrate by way of example the preferred embodiment of this invention, and in which:

Figure 1 is a perspective view of the complete hair clipper, and

Figure 2 is a plan view of the same with the upper cover removed.

Figures 3 and 4 are sectional plan views showing the mounting and means for adjusting the position of the upper cutter relative to the lower, fixed, cutter.

Figure 5 is a side elevation of the cutters showing the two positions of the same.

Figure 6 is a section on line 6—6 of Figure 5.

Figure 7 is a section on line 7—7 of Figure 5.

Figure 8 is a section on line 8—8 of Figure 2, and

Figure 9 is a local section on line 9—9 of Figure 2.

Referring now to the drawings, the hair clipper illustrated therein comprises a lower main casing 10 having an upper cover 11 to enclose the mechanism, this cover being removably held in position by means of a screw 12. The lower cutter 13 is fixed to the forward end of the casing 10 and the upper cutter 14 is oscillated transversely back-

wards and forwards over the same by means of the armature 15 of an electro-magnet 16. The method of driving and mounting of the upper cutter 14 will be more fully described hereinafter. The armature is shaped as shown more clearly in Figure 2, and is mounted at the rear of the casing 10 on a screw 17. The lateral position of the armature relative to the electro-magnet 16 is controlled by the compression springs 18 and 19 which bear one on each side of the same, the spring 18 being adjustable by means of the thumb screw 20 to adjust the position of the armature and hence the throw of the upper cutter. The vertical position of the armature which controls the pressure with which the upper cutter 14 bears on the lower cutter 13 is adjusted by means of a screw 21 (Figure 9) which passes through the bottom of the casing 10 and screws into an extension 15a of the armature beyond the pivot screw 17.

The upper cutter 14 is carried at the forward ends of a bridle piece 25 which is conveniently formed from a length of wire, the forward ends 25a of the bridle piece being turned down and fitting into spaced holes one on each side of the centre line of the same. The bridle piece 25 extends rearwardly in the casing 10 underneath the electromagnet 16 and at its rear end is pivoted on a pin 26.

The attachment of the forward ends of the bridle piece to spaced points on the upper cutter 14, one on each side of the point of drive, will effectively prevent the upper cutter pivoting, even slightly, about the point of drive and, whilst it is true that the actual movement of any point of the upper cutter is an arc of a circle having at its centre the pin 26, the radius of this circle is so large compared with the amplitude of the upper cutter oscillation that for all practical purposes the movement of the upper cutter is a straight line transversely across the lower fixed cutter 13.

The pin 26 on which the bridle piece 25 is pivoted is not fixed to the casing 10 of the clipper but is carried by a crank 27, pivoted at 28 in the casing, and adapted to be controlled from outside the casing by means of a small arm or lever 29. The crank 27 extends beyond the pin 26 and also functions as a stop to limit the backward and forward movement of the bridle piece 25 and upper cutter 14 by engagement with suitable abutments on the casing 10, as shown in Figures 3 and 4.

By moving the external arm or lever the pin 26 forming the pivot point of the bridle piece 25

can be moved towards or away from the front of the device. The required movement is comparatively small and, by suitably disposing the pin 26 relative to the axis 28 on which the crank 27 moves, it can be arranged that the movement of the pin 26 is substantially a straight line although, provided any deviations from the straight line are not substantial, they are of no importance. Backward and forward movement of the bridle piece 25 causes a corresponding backward and forward movement of the upper cutter, as will be readily appreciated.

Friction-tight holding means are preferably provided on the crank spindle 28 to hold the bridle piece 25 against undesired movement when once it has been set.

Referring now to the connection between the forward end of the armature 15 and the upper cutter 14, it will be appreciated that this connection must be such as to allow the backward and forward movement of the upper cutter but, subject to this, any suitable means may be provided for connecting the armature to the upper cutter. It is preferred, however, to employ the means shown in the drawings. As shown, the connecting means comprise a spring retaining or bridge piece 30 shaped at its ends to form grooves 31 taking over the bridle piece. The forward end of the armature 15 is turned around at right angles to the electro-magnet, as at 15b, and is provided with a pin 32 which is shouldered at 33 and provided with a ball-shaped end 34. The ball 34 takes into a hole or dimple 35 in the retaining piece 30 to give the drive. Such a method of connecting the armature to the upper cutter has many advantages. For example, it does not require any slotting of the upper blade. The shoulder 33 on the pin 32, in addition to enabling the pin 32 to be easily riveted or soldered into the end of the armature 15b, bears on the back of the retaining piece 30 and keeps the same in place. The connection is, furthermore, such that it permits of the easy movement of the upper blade backwards and forwards and provides a spring pressure between the upper and lower cutters 14 and 13.

The forward ends of the bridle 25 prior to being turned down as at 25a are preferably cranked as at 25b (Figure 5) so that they lie parallel to the blade 14. This will ensure that an even pressure is maintained between the blades 13 and 14 at all positions of the blade 14.

With a view to ensuring the easy running of the upper cutter, ball bearings 40, as shown in Figure 7, may be provided between the upper and lower cutters.

The thickness of the teeth of the lower fixed comb or cutter 13 increases from the forward edge towards the rear, as shown clearly in Figure 5, and it will thus be seen that, as the upper cutter 14 is moved longitudinally backwards and forwards over the lower cutter 13, it will co-operate with different thicknesses of blades in the lower cutter, and so the clipper may easily be adjusted to cut the hair to different lengths.

Preferably a short-haired brush 50 is arranged around the inside of the front end of the removable cover 11 in order to impede as far as possible the ingress of hair clippings into the casing where they are liable to interfere with the satisfactory working of the apparatus.

The flexible conductor 51 for supplying the electro-magnet preferably enters the casing to one side, as shown in Figure 1, instead of in the middle, as is usual with electric hair clippers.

This will materially facilitate the use of the clippers since the conductor 51 will no longer get in the way of the user's hand. The conductor 51 enters the casing through a rubber sleeve 52 which is gripped between the two parts 10, 11 of the casing, and a loop 53, by means of which the clippers may be hung up, is preferably provided at the further end of this tube. This positioning of the loop 53 will reduce the chance of the clippers being damaged when not in use.

It will, of course, be obvious that the longitudinal position of the upper cutter relative to the lower cutter may be adjusted by other means than those described above, and all such means are to be considered as falling within the scope of the present invention.

I claim:

1. An electrically-driven hair clipper, which comprises, in combination: a casing; a lower fixed comb-like cutter secured to said casing at its forward end, said cutter having teeth which increase in thickness rearwardly, toward the rear end of said casing; an upper comb-like cutter having teeth, said upper cutter cooperating with said lower cutter and mounted in juxtaposition thereto, said upper cutter being adapted to be oscillated transversely with respect to said lower cutter and being provided with two apertures, transversely spaced with respect to each other, at opposite ends of said upper cutter; an electro-magnet mounted in said casing in the forward portion thereof adjacent said comb-like cutters; an armature for said electromagnet, the rearward portion of said armature being secured to the rear of said casing; connecting means at the forward end of said armature, beyond said electromagnet, operatively connecting said armature to said upper cutter, whereby movement of said armature toward and away from said electromagnet moves said upper cutter transversely with respect to said lower cutter to cut hair held within said teeth; a crank pivoted to said casing and adjustably mounted with respect thereto in the rearward portion of said casing, said crank being adapted to be rotated with respect to said pivotal mounting by the application of pressure to one end thereof extending outside of said casing; a pivot pin mounted on one arm of said crank within said casing; and an adjusting bridle piece for adjusting the longitudinal position of said upper cutter with respect to said lower cutter whereby the length of hair cut by said clipper may be regulated, said bridle piece being generally U-shaped in form and having the closed end of the U extending rearwardly of said electromagnet in said casing for a considerable distance beyond said electromagnet, said rearwardly extending portion being pivoted to said crank by extending around said pivot pin, the forward end of said U-shaped bridle piece being bent downwardly at the terminal portions thereof so as to provide two depending bent-over ends, said depending bent-over ends being positioned in said apertures in said upper cutter, whereby rotation of said crank moves said bridle piece forwardly or rearwardly within said casing and moves said upper cutter longitudinally with respect to said lower cutter to regulate the length of hair cut by said clipper.

2. An electrically-driven hair clipper as defined in claim 1, wherein said U-shaped adjusting bridle piece comprises a single piece of wire, and wherein an abutment is provided in said casing for limiting rotational movement of said crank

and longitudinal movement of said bridle piece which is pivotally secured thereto.

3. An electrically-driven hair clipper as defined in claim 1, wherein said connecting means for driving said upper cutter from said armature includes a spring retaining piece in contact with said upper cutter to transmit motion thereto, said retaining piece being provided with a ball-receiving depression on one surface thereof; and a shouldered pin secured to said armature, said pin being provided with a terminal ball-shaped end which is seated in said ball-receiving depression, and said pin being so positioned that the shoulder thereon bears against said retaining piece, thereby keeping said retaining piece in place on said upper cutter. 15
